GUY S. CORNISH, OF CINCINNATI, OHIO, ASSIGNOR TO THE CINCINNATI PATENT ENGINEERING COMPANY, OF CINCINNATI, OHIO, A CORPORATION OF OHIO

RADIOCIRCUITS

Application filed October 4, 1924. Serial No. 741,771.

This invention contemplates the use of a type of radio tube in which there has been provided the usual filament and plate, but in which more than one grid element is associated therewith.

An object of the invention herein described is to produce a circuit in which the use of a tube having more than one grid element will bring about results such as the reception of 10 radio signals with less static and local interference and at the same time with a greater degree of strength and clarity than has heretofore been possible without a corresponding increase in the strength of such objectionable 15 interference as is usually experienced.

A further object is to produce a radio circuit in which tube oscillation is prevented from occurring at times most critical to the proper reception of the radio signal, without 20 having to resort to such devices as neutralizing capacities and similar expedients intended for such purposes.

A further object is to produce a radio circuit in which the principles suggested in the 25 foregoing objects are readily applicable to radio frequency amplification and to detection when tubes having more than one grid are employed.

These and other objects are attained in the 30 invention set forth in the following specification and illustrated in the accompanying drawing, in which:

Fig. 1 is a diagrammatic view of a radio circuit consisting of two stages of radio frequency amplification and a detector, the invention herein having been shown as applied to the radio frequency stages only, the tubes for such purposes having been shown as of the type embodying more than one grid.

Fig. 2 is a diagrammatic view of a detector circuit employing the principle of the invention herein set forth, the detector tube for this purpose being of the type employing more than one grid.

Fig. 3 is a diagrammatic view of a one stage audio amplification circuit suitable for addition to the circuits shown in Figs. 1 and 2.

Fig. 4 is a diagrammatic view of a radio circuit consisting of two stages of radio fre-

quency amplification and a detector, as in Fig. 1, but showing a modification of the connections thereof.

Fig. 5 is a view quite similar to Figs. 1 and 4, but showing a further modification.

The presence of capacity coupling between two electric circuits, as for example, the primary and secondary circuits of a radio receiver as exemplified in the radio frequency primary and secondary transformer coils on the radio frequency amplification end of the usual receiver, results in the transmission of undesirable signal disturbances. Selectivity of the receiver is destroyed and reception of the desired signal is prevented. It is well known that capacity coupling between the grid and plate circuits of an audion or radio tube frequently results in the production of oscillations. Such oscillations are very undesirable, particularly in amplifier circuits, inasmuch as they completely disguise the signal which it is desired to amplify. In

order to overcome the objections to which I have referred, one of the usual methods has been to employ special condensers for the purpose of neutralizing the interelement capacity of vacuum tubes or audions. Such condensers have a low capacity which is approximately equal to the internal capacity of the tube. This relative equality defeats any tendency for a large amount of radio frequency current to pass back through the tube to the grid, but is neutralized by the combination of the neutralizing condensers, the interelement capacity of the tubes and the secondary windings of the radio frequency transformer.

In the invention herein described interelement capacity of the tubes is overcome and capacity coupling of the primary and secondary coils of the radio frequency transformers is eliminated in the new and novel manner set forth. I employ for this purpose radio tubes of the construction embodying more than one grid. In the embodiment of my invention as disclosed in Figs. 1 and 2, I have employed four element or two grid tubes in the radio frequency and detector circuits. In Fig. 1 I have shown the radio frequency amplification circuit as provided with two grid tubes 4 and 5, the detector having been shown as a

single grid or three element tube 6. In Fig. 2 the modification disclosed employs a two grid tube 7 for detection purposes.

The usual symbolic representation of the parts is shown, the antenna 8 being connected as usual through the primary winding 9 of the first radio frequency transformer 10 to the ground 11. The secondary winding 12 of this transformer is provided with the usual variable condenser 13 across its terminals, with one terminal connected to one grid 14 of the tube 4 and the other terminal connected to the negative terminal of the A battery 15. The plate 16 of the tube 4 is connected with one terminal of the primary coil 17 of the second radio frequency transformer 18 while the opposite terminal of the coil 17 is connected with the positive terminal of the B battery 19, the negative terminal of the B battery being connected with the positive terminal of the A battery. The secondary coil 20 of the second radio frequency transformer 18 is connected across its terminals with a variable condenser 21, one of the terminals being connected with one grid 22 of the second tube 5, the other terminal being connected with the other terminal of the A battery 15. The connection of the filaments 23 and 24 of the respective tubes 4 and 5 involves one leg of each being connected with the positive terminal of the A battery with the other leg connected with the negative terminal of the A battery through interposed rheostats 25 and 26 respectively. The additional grids 27 and 28 in the respective tubes 4 and 5 are connected with each other and between them are connected with a tapped connection 29 off the secondary coil of the second radio frequency transformer 18, which connection may be variable as indicated. The plate 30 of the second tube 5 is in turn connected with one terminal of the primary coil 31 of the third radio frequency transformer 32, the opposite end of the coil being connected to the positive terminal of the B battery 19. The secondary coil 33 of transformer 32 is provided with a variable condenser 34 connected across its terminals, with one terminal of the coil connected with the positive terminal of the A battery and the other terminal connected with the grid 35 of the detector tube 6 through the usual grid condenser 36 and grid leak 37. As in all detector connections the filament 38 is connected through one leg with the negative side of the A battery and through the other leg with a rheostat 39 operating on the positive side of the A battery. The plate 40 of the detector tube may be connected directly with one terminal of the phones 41 which have their opposite terminal connected with the 22½ volt connection of the B battery. Across the phone terminals the condenser 42 may be placed as is the usual practice.

65 In the event it is desired to utilize for de-

tection purposes the same type of tube which is employed in the radio frequency stages of amplification, Fig. 2 shows in diagrammatic manner, the connections involved. The filament 43 is connected through the rheostat 39 as in the three element detector connections and the other details, as for example grid 44, plate 45, grid condenser 36, grid leak 37 and variable condenser 34 correspond identically with the corresponding elements 35, 40, 36, 37 and 34 of the three element detector connections. However, the secondary coil 33' of the radio frequency transformer 32' corresponding to the elements 33 and 32 of the previous description, are connected with the additional grid 46 of this type of detector tube by means of a tapped connection 47 on the secondary coil of the transformer, an additional condenser 48 and grid leak 49 being provided in the connection. The connection 47 may be variable for purposes which will be described, as in the case with connection 29. The connection of the plate 45 with the phone circuit is identical with that described in connection with plate 40, but, in the case of either plate the addition of one or more stages of audio amplification is possible by connecting the terminals of the primary coil 50 of the audio transformer 51 to the output terminals of the detector in lieu of the phone, as suggested by Fig. 3. This figure is merely for purposes of illustration and in no manner embodies any features of novelty, and for this reason will not be specifically described.

The functioning of the circuit disclosed depends for its novelty upon the connection of the extra grid in each tube with the secondary located adjacent to and in association therewith. Each of the entire secondary coils 12 and 20 being thrown into the circuit of grids 14 and 22, each of said coils being identical, the two grids 12 and 20 will respond or operate under identically the same conditions of phase or frequency so that they are in step as it were. It is a well known fact that a radio or electron tube may become a source of disturbance through its having been caused to break into oscillations due to regenerative action created by a change of grid voltage which makes a change in plate current of such magnitude that there is induced in the grid circuit a larger voltage than that originally acting. Such oscillations are readily prevented in the invention I have set forth herein, by the presence of the additional grid in each of the radio frequency tubes, which are connected through the secondary coil so as to throw the grid operations out of phase. However the connection of the extra grids with the secondary is not made at the same point as are the grids 14 and 22. In Fig. 1 I have shown one manner of connecting the extra grids 27 and 28 so that they operate in tandem with a single connection 29 which causes their operation to effect a neutraliza-

tion with respect to their companion grids 14 and 22, much as is accomplished in the operation of "neutrodyne" type receivers. This point of connection happens to be shown as at a point in the secondary of less inductance than that of the secondary connections of grids 14 and 22. Such a connection has the effect of preventing the tube from oscillating and thus causing the circuit to be particularly adapted to the reception of signals of relatively short wave length. If on the other hand, the variable connection with the secondary be made with a continuation thereof outside the tuned or main portion across which the variable condensers are placed, as shown in Fig. 4, the effect will be to particularly adapt the circuit to the reception of signals of relatively long wave length.

Further changes in connection may be made by causing each extra grid to operate independently of the other by connecting it to the desired point of the secondary of the transformer to which its companion grid is connected as I have suggested by dotted lines in connection with grid 27 in Fig. 5, instead of connecting the extra grids in tandem. This idea is also suggested in the showing of the two grid detector circuit disclosed in Fig. 2. The particular effect in the case of the detector tube is to clear up the signals so that they may be received with materially greater distinctness and freedom from disturbance than heretofore, in addition to rendering them capable of reception with considerably greater volume.

I claim:

1. A wave signal responsive circuit consisting of alternately associated radio frequency transformers and audions, each of said transformers consisting of primary and secondary coils inductively coupled relatively to each other, each of said audions possessing duplicate grid elements, one of said grid elements having circuit connection with one of said coils, the other of said grid elements having circuit connection with the same coil as to which the first mentioned grid elements are connected, but at a point therein different from and adapted to produce different inductive results from those produced at the point of connection of the first mentioned grid elements.

2. A wave signal responsive circuit consisting of alternately associated radio frequency transformers and audions, each of said transformers consisting of primary and secondary coils inductively coupled relatively to each other, each of said audions possessing duplicate grid elements, one of said grid elements having circuit connection with one of said coils, the other of said grid elements having circuit connection with the same coils as to which the first mentioned of the duplicate grid elements are connected, but at a point therein different from and adapted to produce

different inductive results from those produced at the point of connection of the first mentioned grid elements, one of said audions which are so connected being adapted for use as a detector of wave signals delivered to it by the others, by having one of its duplicate grid elements arranged to cause said audion to function as a detector.

In testimony whereof I have hereunto affixed my signature.

GUY S. CORNISH.
